UNITED STATES PATENT OFFICE.

ANDREW E. SCHMITT AND PETER F. BUCK, OF SANDUSKY, OHIO.

WINDOW RAISER.

Application filed April 3, 1924. Serial No. 703,856.

To all whom it may concern:

Be it known that we, ANDREW E. SCHMITT and PETER F. BUCK, citizens of the United States, and residents of Sandusky, in the 5 county of Erie and State of Ohio, have invented a new and useful Window Raiser, which invention is fully set forth in the following specification.

Our invention has for its object to provide 10 an efficient automobile window-raising device and one wherein the window may be positively locked in any one of a plurality of positions to which it may be raised.

The invention may be contained in window raisers of different forms. To illustrate a practical application of the invention we have selected a structure containing the invention as an example of such structures, and shall describe it hereinafter. The window raiser selected is shown in the accompanying drawings.

Figure 1 illustrates a side view of a door, the inside sheet covering material being shown partly broken away to illustrate a 25 part of the window-raising device. Fig. 2 illustrates a side view of the window raiser and Fig. 3 illustrates an edge view of the device. Fig. 4 is a sectional view, taken on the line 4—4 indicated in Fig. 2, of a wheel 30 used in raising the window.

The window-raising device may be used for raising windows located in the door or any other part of the automobile. In Fig. 1, 1 is a door in which the window 2 is located, 35 the door being provided with suitable guiding channels for maintaining the window in position. The window raiser is secured to the framework of the door, such as to the cross pieces 3 and 4, by means of the screws 5.

40 The device has a sheet metal strip 6 to which the parts are connected and thus the device may be installed in an automobile by merely securing the supporting strip 6 to the frame of the automobile. A vertical rod 7 is secured to the strip 6 near the upper and lower ends thereof by means of the posts 8 that secure the rod parallel to and in spaced 45 relation with respect to the strip 6. A lazy-tongs 10 may be pivotally connected to a suitable fixed pivot pin located at any point in the lazy-tongs. In the form of construction shown, the tongs are provided with two sets of links and is pivoted to a fixed pin located in line with the center pivot pins or 50 points of the lazy-tongs. The lazy-tongs 10 may be provided with any number of sets of

links to produce any desired upward movement relative to the movement of any one set of the links. The post 8 located at the lower end of the rod 7, has a cylindrical portion 60 or a pin 9 and the lower links of a lazy-tongs 10 are pivoted on the pin 9. A bushing 11 may be located on the pin 9 to hold the lower links of the tongs 10 in position, and yet permit pivotal movement of the links. Another of the center pivot pins is provided with a head 12 having a bore for receiving the rod 7 whereby the movement of the lazy-tongs is guided along the rod 7. The pin 13 having the head 12 is connected to a 70 means for raising and lowering the lazy-tongs. In the form shown, it is connected to the cable 14 by means of the cable connector 15 having an opening for receiving the pin 13 and which may be forced on to 75 the pin 13 to securely connect the cable to the pin.

The cable 14 extends to a wheel 16 having a groove 17 located in its edge. One end of the cable 14 is secured to the wheel 16 and a 80 portion of the cable lies within the groove 17. When, therefore, the wheel 16 is rotated the cable 14 is drawn upwards which raises the lazy-tongs. The weight of the lazy-tongs and the parts connected thereto will 85 lower the lazy-tongs when the wheel is rotated in the opposite direction. An arm 18 may be connected to the wheel for the purpose of rotating the wheel. The wheel may be pivotally supported between the strip 6 90 and a bracket 19 having suitable bearings for receiving the pin or shaft 20 to which the arm 18 is connected.

The upper center pin of the lazy-tongs is also provided with a head 21 having a bore 95 through which the rod 7 extends to guide the upper portion of the lazy-tongs and to maintain the lazy-tongs in parallel relation with respect to the rod 7. A bracket 22 is connected to the head 21 having an upwardly extending flange 23. The window 2 is provided with the usual supporting channel bar 24 extending across the lower edge of the window 2.

100 The inside of the channel bar is provided with a lip 25 that is turned downward and which may be placed on the flange 23 of the bracket 22. Thus the bracket 22 sustains the weight of the window 2 and connection is made between the window 2 and 110 the window-raising device.

In order to positively sustain the window

in any one of a plurality of positions to which it may be raised by the rotation of the wheel 16, means is provided for locking the window. In the form of construction shown the window-raising device is provided with a flat bar 26 that may be formed from sheet metal and which is pivoted by means of the pivot pin 27 near the upper end of the rod 7. The bar 26 is provided with notches 28 for engaging the inner end of the pin 13. The bar 26 may be pivotally connected to the strip 6 so as to cause the bar 26 to normally swing towards the pin 13 and so as to place the notches 28 in position of engagement with the pin 13 except when the bar 26 is positively swung away from the pin 13. Thus the upper end of the bar may be provided with a laterally extending arm 28 in which the pin 27 is located and also the bar 26 may be provided with a widened lower end to load the lower end of the bar on the side opposite to that from which the arm 28 extends. To guide the bar 26 and maintain it in its position notwithstanding its lateral swinging movements, the lower end of the bar may be provided with a slot 29 in which a fixed pin 30 secured in the strip 6 may be located. The pin 30 may be provided with a suitable head to retain the bar in position on the pin. Also if desired, and in order to prevent rattling of the bar as the automobile proceeds over the road, the bar may be elastically drawn towards the pin 13 by means of the spring 31 which is connected at one end to the bar 26 and at the other end to the strip 6.

In order to positively move the bar 26 to release its engagement with the pin 13, the periphery of the wheel 16 is provided with a plurality of lugs 32 which engage the edge of the bar 26 to swing it away from the pin 13 when the window is to be lowered. Thus the notches 28 are suitably formed in the bar with respect to the position of the lugs 32 on the wheel 16 at such

points that the pin 13 will reach the succeeding notches 28 in advance of the times when the lugs 32 engage the bar 26 during the lowering of the window, the opposite being true when the window is raised. By this arrangement the window may be raised to any one of a plurality of points and the pin 13 will be engaged by the bar 26. When the window is to be lowered, a lug 32 will first push the bar 26 to one side and there being some lost motion in the parts. When the bar 26 is pushed to one side the load of the window operating through the lazy-tongs is placed upon the cable 14.

We claim:

1. In a window-raising and lowering device, lazy-tongs connected to a fixed pivot pin forming one of the central pivot pins of the lazy-tongs, another central pivot pin of the lazy-tongs for connecting the window to the lazy-tongs, a cable connected to another of the central pivot pins, means for operating the cable to raise and lower the window and a dog having a plurality of notches for engaging one of the central pins of the lazy-tongs for securing the lazy-tongs in any one of the plurality of positions to which it may be moved by the said means.

2. In a window-raising and lowering device, lazy-tongs connected to a fixed pivot pin and to the window, forming one of the central pins of the lazy-tongs and connected to the window by another of the central pins of the lazy-tongs, a rotatable member connected to another of the central pivot pins of the lazy-tongs, a dog for securing another of the central pins of the lazy-tongs in the position to which it may be moved by the said member, and said member having lugs for engaging the dog and to release the dog from the central pin with which it is in engagement.

In testimony whereof, we have hereunto signed our names to this specification.

ANDREW E. SCHMITT.
PETER F. BUCK.
